CLAIM

The ornamental design for a garden stand, as shown and described.

DESCRIPTION

FIG. 1 is a front perspective view of a garden stand showing my new design; the rear side view thereof being a mirror image;

FIG. 2 is a right side view thereof, the left side being a mirror image;

FIG. 3 is a top plan view thereof; and,
FIG. 4 is a bottom plan view thereof.

1 Claim, 2 Drawing Sheets
